THERMO-ELECTRIC APPARATUS FOR HEATING COMPOUNDS
USED FOR DENTAL IMPRESSIONS
Filed June 9, 1941

2,316,287

This technical drawing illustrates a complex mechanical assembly, possibly a press or stamping machine. The main structure is a vertical column supported by a base (44) with a central vertical axis (1). Key features include:

- A vertical cylinder (30) with a rod (31) extending downwards.
- A horizontal cylinder (40) at the top, connected to a lever system (41, 42, 43).
- A vertical pipe assembly (21, 22, 23, 24, 25, 26, 27, 28) on the left.
- A vertical pipe assembly (5, 32, 33, 34, 35, 36, 37, 38, 39, 40, 41, 42, 43, 44, 45) on the right.
- A base plate (22) with a central hole (23) and a side support (24).
- A circular detail at the bottom right showing a central hole (1) surrounded by a ring of holes (8) and a outer ring of holes (10, 11, 12).

The drawing is annotated with numerous numbers (e.g., 1, 5, 10, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, THERMOELECTRIC APPARATUS FOR HEATING COMPOUNDS USED FOR DENTAL IMPRESSIONS

Jose Mendez Ribas, Buenos Aires, Argentina

Application June 9, 1941, Serial No. 397,322
In Argentina January 13, 1941

5 Claims. (Cl. 219—38)

The present invention relates to an apparatus adapted for the preparation and maintenance of elastic compounds, defined as pastes capable of being utilized for dental impressions. This apparatus tends to simplify dentists' work from the moment that it allows them to have at his disposition from one to five units of new or old elastic compound, quite ready to be applied at the ideal temperature for the mouth, in contrast with the elementary independent systems actually known and based on a syringe heater for one sole unit (one impression), and which oblige a professional to delay twenty minutes in their preparation without any scientific control of temperature, while the apparatus which is the object of this invention, permits of obtaining up to eight successive impressions.

The apparatus in question, comprises a tubular member in which is placed the material to be used; this tubular member is associated with a receptacle, for containing hot water, the receptacle being arranged axially in the form of an external cover, in which are provided means for the electrical heating of the water to a predetermined temperature, the apparatus being completed by other elements arranged in the form hereinafter detailed in a whole in accordance with the accompanying drawing in which:

Figure 1 is a general view of the apparatus in vertical section along the axis showing the form in which its elements are arranged.

Figure 2 is a sketch of the detail of the electrical connection circuit of the apparatus with the source of supply.

Figure 3 is a partial detail of the apparatus in cross section through the line A—A of Figure 1.

The apparatus, according to the design shown in the accompanying drawing, comprises the following arrangement of parts: a tubular member 1, which ends in a base plate 2, to which is soldered a receptacle 3, the container of the hot water which causes the softening of the paste. The lower end of part 1 is suitably threaded for a screw connection to a cover 4, and at its upper end said part 1, includes a threaded portion for the connection by a screw of a coupling 5, fixed to the inside part of a curved top 6, the screwing of which upon part 1, is effected by moving a hand knob 7, fixed to one of the sides of said top.

Within part 1 there is arranged so as to have a free lineal movement, a beater, comprised of a disk 8, provided in its surface with multiple holes 9; Figures 1-3, and in two of its diametrically opposed ends said element 8, is provided with two

indentations 10 on which rests a corresponding stop 11, fixed by its vertical projection 12, to the base of a piston 13, which moves freely on a rod 14, fixed to the element 8 which rod projects through the top 6, ending in a manually operated knob 15, fixed to said rod by means of a retaining collar 16.

Element 4 is provided with a central aperture 17, suitably tapped, and which forms the path of discharge of the material, said aperture being capable of being closed by a valvular member 18, which includes a stem 19, projecting to the exterior of an under cover 20, provided with a central cavity 21, also tapped with a thread identical with that of the aperture 17, in order to receive the member 18 in the same, when it is operated by the outside part of the bottom cover 20 by means of a manually operated knob 22, which forms the lower extreme end of the rod 19, the bottom cover 20, being connected by one of its ends and with free rotary movement to element 4, by means of a pin 23, adjustable in position by a hand knob 24, including at the opposite end of the bottom cover 20, an indentation 25, formed in the radius of action of a stop 26, projecting from element 4, said stop forming the means of limiting the open play of the bottom cover to the limit required until the obtaining of the total aperture of the discharge opening 17.

The receptacle 3 includes in the upper portion of one of its sides, a tubular member 27, which ends in a basin 28, in which is placed the water with which the said receptacle is to be charged, to which the tubular member 27 is connected by screwing to the coupling 29, fixed to the receptacle 3, with which it communicates the passage determined by element 27, through an admission orifice 30, made in said receptacle, which towards its lower end is provided with a cock 31, through which the emptying of the receptacle is effected when this may be necessary.

The upper opening of receptacle 3, is closed by a disc cover 32, adjusted by a central perforation made in the same, against the external surface of element 1 to which said cover is soldered, fixed by its external edge, against a cap in the form of an inverted truncated cone 33, fixed by a corresponding ring ridge; lower end 34, and upper end 35 to the upper opening of the receptacle 3 and the upper end of a segment of the cover 36, which by its lower opening is connected coaxially with the upper opening of a complementary cover 37, and they are fixed reciprocally to each other by means of a ring union

33 Both coverings 36—37, define conjointly with the outside surface of the receptacle 3, a chamber for the containing of the heating elements of the receptacle which in its turn by radiation, transmit heat to the water contained in same.

Cover 6, suitably fixed to the upper opening of the segment of the cover 36, by means of a ring base 39, to which said cover is firmly fixed by a lower end ridge 6a, formed in the same by stamping, includes in its central part a bush 40, in which the rod 14 is guided in its line of lineal movement. This bush bears connected horizontally to it by a screw thread the pin 41, of a stem 42, which ends in a manually operated knob 43, by means of which stem 42 and pin 41 are operated so as to fix the stem 14 on the bush with the beater 8 at a determined height in element 1, in accordance with the volume of compound to be discharged as the necessities of the professional may determine.

The apparatus is provided with a pair of supporting columns 44, fixed to a supporting platform 45, the length of the columns 44 being fixed in such a way as to leave between the discharge opening 17 and the platform 45, a sufficient space to permit of the free placing of the tray for the elastic compound in the zone of discharge of said opening. The apparatus is complemented by means of electric heating of the receptacle 3, which, by radiation, transmits the heat to the water contained in same, which in its turn, causes the heating of the tubular member 1, which by radiation produces in its turn the softening of the elastic compound. These means of heating comprise: an electrical resistance 46, coiled round a sheet of dielectric material 47 fixed to a sheet of same material 48, fastened conjointly with the element 46—47, to the outside part of the lower zone of the receptacle 3, with the interposition of an additional sheet of dielectric material 49, by means of a band 50. The resistance 46, is connected directly by one of its terminals 51 (see Figure 2) to the plug 52, whilst its opposite terminal 53 is connected to a thermostatic plate 54, the contact of which 55 is in front of a similar contact 56, fixed to the upper end of a plate of opposite pole 57, connected directly in an electrical circuit with the complementary plug 58, said electrical connection between plates and plugs being established by means of corresponding conductors 59 and 60, fixed at the lower end of said plates and the after end of the plugs, by common elements fixed by screwing on to the base of pins, nuts and locking-nuts respectively; the plugs 52—58 forming the means of an electrical connection of the apparatus with the installation of the source of current by common intermediary elements of connection.

Both plates 54—57 conjointly with the supplementary plate 61 which operates on the after part of plate 57 are fixed to a support 62 fastened by soldering to the outside part of the receptacle 3, the fixing of said plate to the support being carried out by the interposition between same of interspacing sheets of dielectric material 63, by means of a pair of pins 64, which fix to said group a frontal support 65, towards the upper end of which is joined by a screw the rod 66, which constitutes the means for regulating the initial distance between the contacts 55—56, and consequently the means of controlling from the maximum of temperature to a predetermined degree of the water contained in the receptacle 3, for which purposes said rod is moved by means of a manual-

ly operated knob 67, which operates in the radius of action of a quadrant 68, which will be provided with a scale with indications of distinct degrees of temperature in accordance with indications of a thermometer 69, visible from the external portion of the segment of the cover 36, said thermometer being connected with a metal box 70 fixed towards the upper end of the receptacle 3, virtual contact being made between its after end and the tubular member 1.

15 Plate 61 on being bent by the increase of temperature in the apparatus causes pressure on plate 57, by means of a push stop 71, which operates in contact with insulating sheet 72, fixed to the after part of plate 57, and in the same form; the entering end of the rod 66, causes pressure against insulating sheet 73, fastened to the front space of plate 54.

20 The working of the apparatus proceeds in the following way; the cover 6 is taken off, operating same by means of element 7, and the rod 14 being taken out together with said cover next the elastic compound is placed within the tubular member 1, in sufficient quantity to fill said tubular member as far as necessary; now the cover 6 is replaced in its tight position by screwing its union on the upper end of the tubular member 1, the elastic compound remaining below the beater 8, on which the piston 13 acts; the receptacle 3 is 25 filled with a quantity of water equivalent to 280 cubic centimetres; the apparatus is connected to the electric current until the water begins to boil, the steam generated by the boiling reaching the outside by passing through elements 27—28, and in the space of a quarter of an hour, more or less, the elastic compound is in a fit state for use for dental impressions, since in that space of time it has reached the required degree of softening, the same being beaten by the beater 8. Later on the 30 electric current is cut off and is connected to the thermostat at 160° F. cold water being added to the receptacle, until same runs into the basin 28, in which the water is maintained at a constant temperature of 140° F. the same being destined for the object of impregnating the professional's finger, in order to effect the smoothing of the elastic compound with which the tray is charged, the bottom cover 20 being opened for this purpose after having rotated member 18, by means of the 35 manually operated knob 22, until same remains tight within the cavity 21 of the bottom cover, which is opened by moving said manually operated knob, until the indentation 25 of same rests upon the stop 26, which forms the maximum opening of said bottom cover, which is rotated in the opposite direction, once the tray has been charged, the nuclear element 18 being returned to the position indicated in Figure 1, the charging of the tray being carried out in the following manner: the operator joins to each other piston 13 and beater 8, by fitting elements 11, into the indentations 10 of the beater; he lowers element 13, as far as the cavity 21 of the bottom cover, fixing the opening of the bottom cover in the manner hereinbefore specified, at which moment he fixes the stem 14, by means of the threaded pin 41, together with elements 8—13 at a given height of the tubular member 1, in relation to the quantity of elastic compound required for the impression, after which he returns elements 20 and 18 to the position indicated in Figure 1, moving the same in the manner hereinbefore specified and under these conditions the professional man has elastic compound ready for use at his disposition during consulting hours.

It is evident that within what has been described and represented in the accompanying drawing there may yet be introduced modifications with regard to the constructional form and functional arrangement amongst the elements forming part of same, these being eventualities which the inventor reserves the right to put into practice, without, for this reason, passing beyond the limits and scope of what has already been specified.

I claim:

1. A thermo-electric apparatus for heating elastic compounds utilised for dental impressions, which comprises a central tubular covering for containing the elastic compound, a receptacle for containing the water for heating the elastic compound within the tubular covering, which said receptacle surrounds; a complementary outside covering which surrounds the receptacle which contains the water for heating the elastic compound, between which cover and receptacle there is formed a sleeve provided with means for the electrical heating of the receptacle, means of access to the water within the receptacle and means for emptying the receptacle, there being included within the central tubular cover, means for beating the elastic compound, means for closing the discharge opening for the elastic compound through the central tubular covering; means for slowing and regulating the discharge of the elastic compound to a predetermined volume and a thermostatic group for equalizing the temperature of the water at the predetermined maximum of a visible control.

2. A thermo-electric apparatus for heating elastic compounds used for dental impressions which comprises a central tubular covering for containing the elastic compound, a receptacle for containing the water for heating the elastic compound within the central covering, said receptacle surrounding said tubular covering in spaced relation, a complementary cover which surrounds the receptacle for containing the water for heating the elastic compound and which includes at one end a shut-off disc-top for closing the upper opening of the receptacle, a cap fixed on the upper opening of the receptacle and an external cover on which is fixed the disc-top and an external top connected by a screw threaded connection to the central tubular covering, said external top covering said disc-top and cap and including manually operable means for its connection to and disconnection from the central tubular covering.

3. A thermo-electric apparatus for heating elastic compounds used for dental impressions, which comprises a central tubular covering for containing the elastic compound, a receptacle for containing the water for heating the elastic compound within the central tubular covering, a complementary covering, which surrounds the receptacle for containing the water for heating

- the elastic compound, which comprises the inclusion within the central tubular covering, of means for beating the elastic compound, these means being composed of a disc with multiple perforations fixed to the extreme end of a rod, provided with a counterweight piston freely movable along the rod, said rod including at the end projecting from the outer cover means for slowing the discharge of the elastic compound to a predetermined volume depending on the relative distance between the means for beating and the bottom of the central covering at which distance said means are fixed by the anchoring of the rod to the outside top by means of retention actuated by a screw and defined by a bush united to the casing and through which the lineal movement of the rod is governed, and the threaded end of a pin moved by manual action on a knob, fixed to said pin, the rod being provided at its upper end with a knob for manual operation.
4. A thermo-electric apparatus for heating elastic compounds used for dental impressions, which comprises a central tubular covering for containing the elastic compound, a receptacle for containing the water for heating the elastic compound within the central tubular covering, a complementary covering which surrounds the receptacle for containing the water for heating the elastic compound, a bottom wall for said central tubular covering provided with a central aperture which forms the discharge opening for the elastic compound, a cover having a central cavity rotatably attached to the underside of said bottom wall, a blocking member normally positioned in said discharge opening and adapted to be moved into the cavity of said cover, whereupon said cover is adapted to be moved into open position, a manually operated knob fixed to the lower end of a rod projecting downwardly from said blocking member passing through said cover, and a stop for limiting the rotary movement of said cover to the maximum degree of aperture required.
5. A thermo-electric apparatus for heating elastic compounds used for dental impressions, which comprises a central tubular covering for containing the elastic compound, a receptacle for containing the water for heating the elastic compound within the central tubular covering, a complementary covering which surrounds the receptacle for containing the water for heating the elastic compound, which comprises the inclusion within the central tubular covering, of means for beating the elastic compound, including means for reciprocal union between the beating element formed by a disc provided with multiple perforations and a counterweight piston these means being completed by axial stops projecting from the base of the piston in the position of rest fitting in orifices made in the beater.
